BABY CHICK SHIPPING BOX

Russell R. Harness, Elwood, Ind.

Application March 22, 1946, Serial No. 656,378

3 Claims. (Cl. 229—15)

1

This invention relates to containers, generally, and concerns itself primarily with vented boxes of the type in which fowl, such as baby chicks, are transported.

It is a general object of the instant invention to provide a box having partitioned compartments therein which are individually accessible through flap closed openings in a removable cover of the box.

It is a further object of the invention to provide a partitioned box suitable for the transportation of live fowl which is absolutely safe and which assures absolute segregation of the stock shipped.

Still another object of the invention is to provide an improved shipping box suitable for the transportation of live objects, such as baby chicks, having partitioned compartments individually accessible through flap closed openings in a removable cover of the box, which flaps are adaptable to positive sealing and further are supported by the partitions of the box in a manner to prevent their infolding.

Yet another object of the invention is to provide an improved cover or lid for a partitioned box having individual compartments therein, which cover is provided with a plurality of flaps cut in a manner whereby said flaps are individually supported by the partition walls of the box and are further adapted to be sealed in pairs by an improved stapling device.

A further object of the invention is to provide a box cover having openings therein which are closed by flaps cut in sections forming pairs, one section having two of its sides completely severed from the cover material, and two other of its sides creased for bending, said creased sides forming the hinged portions of said flaps, and the individual flaps being formed by severing the section material lying between the two creased sides along a line offset from its mid-point and parallel with the creased sides for a distance approximately half of the width of said flap, thence, normal to said creased sides for a distance approximating the length of one of said creased sides, then again, parallel to the creased sides to the next line of severance. The material may be such that a hinge line can be obtained without actual creasing of the material.

Other objects and advantages will become apparent as the description proceeds and a more comprehensive understanding of the invention will be afforded from the following detailed specification, which may be considered in conjunction with the accompanying drawings, in which—

2

Fig. 1 is a plan view of a box embodying the instant invention;

Fig. 2 is a side view thereof; and

Fig. 3 is a perspective view of the box illustrating features of its novel cover construction.

In the transportation of live fowl, such as baby chicks, it is the practice of shippers to use vented cardboard boxes as transporting coops. Although numerous types of boxes have been proposed, the one most commonly used is a flat rectangularly shaped box which usually is divided into four compartments. The box itself is covered by means of a lid which may be removed from the box in one complete section, and, due to this construction, some serious problems have presented themselves in its use. In the first place, and particularly in connection with the transportation of pedigreed fowl, it is necessary that they be segregated according to strain, sex, size, age, and other categories. With the prior art box, it has been found that segregation is very difficult to maintain during the loading of the compartments. The extent of this problem can be appreciated more fully with a knowledge of the actions displayed by baby chicks in attempting to free themselves from enclosures. During loading, it is necessary to first fill one of the compartments, then cover that compartment, as well as can be done, with a portion of the lid until the next one is filled, and so on until all of the compartments are loaded. During this proceeding ample opportunity is afforded for the baby chicks to jump from one compartment to the other, and out of the box.

Further, such procedure makes it necessary to place the lid on the box after the compartments are filled with chicks. Because chicks, after a day or two of life, are active and tend to jump over the walls and partitions, there is a danger of crushing and killing them when the lid is placed on the box.

Both of these problems can be, and are, solved by making openings in the box for each compartment. It is desired, however, that the cost of the box shall not be increased and that any closing means used for the separate openings shall not be subject to infolding; shall not require additional supporting means that will interfere with the spaces within the box; or lie outside the box so that the containers have irregular surfaces, and that they be adapted to quick and positive sealing. All of these conditions are met and the problems resolved in the structure now to be described.

As illustrated in the drawings a flat box 11 of the usual size and construction is provided.

This box is divided into four compartments 12, 13, 14 and 15, by two partitions 16 and 17. A cover 18 is also provided for the box which is removable therefrom in one piece.

Although not limited to the use of any particular material the box is preferably made of paper taking any of the well known forms, such as pressed board, cardboard, or corrugated board. The cover has four flaps 19, 21, 22 and 23, which open respectively into the compartments 12, 13, 14 and 15. The flap 19 is cut from the paper cover along the lines 24, 25, 26, 27 and 28. It hinges substantially on the line 29 which for convenience may be creased, depending upon the material used. The flap 21 is, of course, formed by slits along the lines 25, 26 and 27 which are common to the flap 19, is additionally cut along the lines 31 and 32 and is hinged along the line 33 for folding.

The flap 19 has two holes 34 and 35 cut therein which are aligned, respectively, with companion holes 36 and 37 in the flap 21. These holes are adapted, in pairs 34-36 and 35-37, to receive metal clamps 38 which securely fasten the flaps together against opening.

It will be noted that the common lines of severance of the flaps 19 and 21 form extensions for each of the flaps which lie above, and are supported by a section of the partition wall 16 separating the compartments 12 and 13. In this manner both of the flaps are protected against infolding due to the supporting action of the compartment wall.

The flaps 22 and 23 are formed identically with the flaps 19 and 21, and the entire box is vented by means of a plurality of holes 39 cut in the sidewalls of the box and in the cover, as shown.

With reference to Fig. 3, which shows the flap 19 in its raised position, it will be seen that the compartment 12 is individually accessible through the opening covered by the flap. It will be noted also that all of the other compartments, particularly compartments 14 and 15, are closed. True enough, a small opening into compartment 13 extending between the line 27 and the wall 16, is uncovered but this opening is of such dimensions as to prevent fowl from passing through it. Even if it were large enough for such passage, it is so positioned with relation to the compartment 12 that it may be easily watched, or closed by the hand or the flap, during the filling of this compartment.

In cases where segregation is not important, the flap openings may be used for loading, only, to prevent injury to the chicks and then clamped closed. When the box reaches its destination the cover of the box may be removed in one piece and the compartments quickly emptied. Where it is important to keep the contents of each compartment separate, the chicks may be removed through the flap openings. The box is thus adaptable to all requirements, is economical, prevents the loss of fowl, and saves the time of the shipper in loading and that of the receiver in unloading.

While a preferred embodiment of the invention has been illustrated and described it is possible the same may be practiced in other ways without departing from its basic concepts. Insofar as all modifications and changes to which the invention is susceptible fall within the scope of the appended claims they are considered to be covered as if described.

What is claimed is:

1. In a box like container having a plurality of compartments formed by partition walls and collectively accessible by the removal of a cover for said box, means providing for the individual accessibility of each of said compartments comprising a plurality of flaps cut in the cover of said box and hinged for opposed movement in pairs to close openings therein communicating with said compartments, each of said flaps having an extension thereon supported by one of the partition walls of said box, and clamping means insertable in said flaps to secure them in their closed positions.
2. In a cover for a chick box having a plurality of compartments therein formed by partition walls, a plurality of flaps for closing separate openings in said cover each opening communicating with one of said compartments, said flaps being cut in sections from said cover and forming flap pairs, one section having two of its sides completely severed from the cover material and two other of its sides creased for bending, said creased sides forming hinges for the said flaps and clamping means positionable in aligned openings in each flap of said pair for clamping them in their closed positions.
3. In a box like container having a plurality of compartments formed by partition walls and collectively accessible by the removal of a cover for said box, means providing for the individual accessibility of each of said compartments comprising a plurality of flaps cut in the cover of said box and hinged for opposed movement in pairs to close openings therein communicating with said compartments, each of said flaps having an extension thereon supported by one of the partition walls of said box, and fastening means securing the flaps to each other in edge abutting position, thereby forming a closure.
